UNITED STATES PATENT OFFICE.

JOSEPH SPITERI, OF WINNIPEG, MANITOBA, CANADA.

DIRIGIBLE AIRSHIP.

1,134,241.

Specification of Letters Patent.

Patented Apr. 6, 1915.

Application filed August 31, 1914. Serial No. 859,302.

To all whom it may concern:

Be it known that I, JOSEPH SPITERI, of the city of Winnipeg, in the Province of Manitoba, Canada, have invented certain new and useful Improvements in Dirigible Airships, of which the following is the specification.

The invention relates to improvements in dirigible balloons and the objects of the invention are as follows: to provide an improved form of gas container or body which will effect great stability and presents a plurality of distinct compartments all connected, but arranged so that they can be closed off one from the other: to provide an expansion chamber in combination with and connected to the gas container arranged to receive the gas discharged automatically from the gas container by reason of the natural tendency of the gas to expand due to changes in pressure in the varying altitudes: to provide an improved form of steering mechanism whereby the airship may be readily navigated, the complete mechanism being under the control of a single attendant and being particularly positive in its action: to provide an improved means of propulsion and propelling mechanisms in tandem, the latter being arranged so that they can be operated independently or together and when operating together will act in synchronism: to provide a device in connection with the propelling mechanism and the propellers which will effect the driving of the propellers upon the propelling device or engine reaching a certain predetermined speed of rotation: and lastly to provide a dirigible airship having the body thereof constructed to cut through the air in flight with a minimum amount of resistance and designed further to provide ample accommodation for passengers, pilots and fuel while retaining proper balance.

With the above objects in view the invention consists essentially in the arrangement and construction of parts hereinafter more particularly described and later pointed out in the appended claims.

Figure 1 represents a side view of the complete airship. Fig. 2 represents a plan view. Fig. 3 represents a rear end view. Fig. 4 represents an enlarged detailed vertical sectional view. Fig. 5 represents an enlarged detailed perspective view of the steering rudder. Fig. 6 represents an enlarged detailed side view of the steering

post, associated and adjoining parts. Fig. 7 represents an enlarged detailed vertical sectional view through a portion of three gas compartments in different sections showing the manner in which they are connected. Fig. 8 is an enlarged detailed side view of one of the levers located in advance of one of the engines. Fig. 9 is an enlarged detailed vertical sectional view of the spring depressed locking pin connecting the levers. Fig. 10 represents a side view of the parts appearing in Fig. 9. Fig. 11 represents an enlarged detailed side view of a portion of the cross shaft controlling the elevating rudder. Fig. 12 represents an enlarged detailed vertical sectional view through the clutch members on the engine shaft. Fig. 13 represents an enlarged detailed face view of the female clutch member and adjoining parts. Fig. 14 is an enlarged detailed plan view of the engines showing the adjusting rod controlling the gasoline feed to the engines. Fig. 15 represents a face view of one of the engine carburetors. Fig. 16 is an enlarged detailed vertical sectional view of the gas pipe and contained valves appearing between the gas container and the expansion chamber. Fig. 17 represents a plan view of the quadrant associated with the levers. Fig. 18 represents a side view of a portion of the quadrant. Fig. 19 is an enlarged detailed side view of one of the levers and adjoining parts located to the rear of the engines.

In the drawings like characters of reference indicate corresponding parts in each figure.

1 represents the body or gas container of the dirigible formed from a suitable frame structure inclosed within an envelop and presenting a more or less cylindrical body with rounded ends and a pair of longitudinally extending outstanding wings 2 and 3. Within the body I have reserved space for an engine room as indicated at 4 and directly beneath the engine room I have located a cabin 5, a storage compartment 6, pilot house 7 and a wireless room 8, these all being approached through a centrally located entrance way 9. In the flooring beneath the engine room I have fitted a tank 10 for gasoline or other such fuel.

11 is a promenade deck associated with the cabin.

The gas chamber is divided into a number of distinct compartments by internal par-

titions passing between the walls of the engine room and the envelop. In the present instance the body is divided by three vertically disposed partitions 12, 13 and 14 into four sections, a forward section 15, two central sections 16 and 17 and a rear section 18. These sections are distinct and are again subdivided by partitions 19 into distinct compartments 20, 21, 22, 23, 24, 25, 26 and 27, these latter compartments being best shown in Fig. 4 of the drawing. In the present dirigible I have in this way provided thirty-two distinct compartments. It will here be noticed that the compartments 21 and 26 open to the wings 2 and 3 in each division.

28 is a main gas supply pipe passing along the engine room and 29, 30, 31 and 32 are branch pipes leading from the main pipe 20 and connected by means of similar valves 33 with the respective compartments in each section.

The supply pipe is fitted with a main valve 34 while the extending ends of the branch pipes are supplied each with a controlling valve 35 with the result that when the respective compartments are inflated or filled with gas and the main and controlling valves closed the gas cannot escape from the compartments. The adjoining sections are connected one to the other by spanner pipes 36 fitted with valves 37, there being a spanner pipe fitted with a valve connecting each similar pair of compartments adjacent to each other on opposite sides of the transverse partitions.

Owing to the above arrangement of valves I am able at any time to cut off one section from another or any compartment from the others. The object of this is obviously to allow of the repair of any compartment without effecting the other compartments. For example if the envelop became torn at any point I am able by manipulating the valves to close off the compartment where the tear appears and the gas will only escape from the one compartment and not from the others.

38, 39 and 40 are pairs of independent gas compartments located in the ceiling of the engine room and independently inflatable from the main supply pipe.

41 is an expansion chamber mounted on the top of the body and opening to the same through forward and rear pairs of gas pipes 42 and 43. The pipes each contain a spring pressed ball valve 44 which controls the passage of the gas from the container to the expansion chamber and a spring pressed pop valve 45 which controls the escape of the gas from the expansion chamber to atmosphere.

I might here explain that heretofore in ascending to higher altitudes it has been necessary, owing to the drop in pressure, to release a certain amount of the gas with

which the envelop is inflated to avoid the possible destruction of the envelop due to the expansion of the gas. This gas is consequently lost. In my airship the springs controlling the valves 44 are constructed such that the gas is permitted to expand into the expansion chambers when higher altitudes are reached. The above avoids releasing the gas as the action is entirely automatic and it also effects the saving of the gas as it is now allowed under ordinary conditions to escape to atmosphere. In event of an exceptionally high altitude being reached and the capacity of the envelop and the expansion chamber being not sufficient to accommodate the gas, then under this condition the gas is allowed to escape to atmosphere through the valves 45, the springs controlling these valves being designed to operate to release the valve when the gas pressure is sufficiently great.

46 is an elevating rudder located at the front of the body and pivotally mounted on a pair of brackets 47 extending from the body.

48 is a cross shaft rotatably mounted in the forward end or nose of the envelop and provided centrally with a chain wheel 49 and at either end with extending cranks 50 fitted with pins 51 operating in slots 52 located within the ends of arms 52 extending rearwardly from the elevating rudder.

52² are cushioning springs connected to the rear ends of the arms and to the framework of the body at points above and below the arms.

53² is a socket mounted on the floor of the pilot house and 53 is a steering post mounted in the socket and supplied with a worm 53² and a hand wheel 53².

54 is a sleeve rotatably mounted on the steering post and fitted with a worm 54² and a hand wheel 54².

A pair of standards 55 are mounted in the floor of the pilot house at opposite sides of the socket and carry a pair of shafts 55² and 55², the shaft 55² being supplied with a worm wheel 55² meshing with the worm 54² while the shaft 55² is fitted with a worm wheel 55² meshing with the worm 53². A chain 56 connects the chain wheel 49 with a similar chain wheel mounted on the shaft 55². By manipulating the hand wheel 54² I am able to elevate or depress the elevating rudder as it will be seen the chain 56 will operate the cross shaft and swing the cranks to effect the turning of the arms 52 and the consequent movement of the elevating rudder. The springs are supplied to retain the elevating rudder in a horizontal position in event of the rudder controlling apparatus breaking.

57 is a steering rudder located at the back end of the envelop. It is constructed as now described.

58 is a substantially rectangular frame carried by suitable arms 58' attached to the body of the airship. Within the frame I have mounted a plurality of similar vertically disposed swiveled rectangular rudder blades 59 connected one to the other by a connecting strip 60 which causes the said blades to turn together. The lower pivot of the central blade projects beyond the frame and is formed into a T-head 59' to which I have connected cables 61 and 61' which pass forwardly under suitable guide rollers to the pilot house where they are wound on and connected to a drum 61² fixed on the shaft 55². By this construction the rudder is completely controlled by the hand wheel 53^x. The construction above described provides a very convenient control both for the elevating and the steering rudders.

62 and 63 are internal combustion engines of any approved type mounted in the floor of the engine room.

62' and 63' represent the engine shafts.

64, 64', 65 and 65' represent pairs of front and rear outstanding propeller shafts rotatably mounted in suitable brackets 66 secured to the sides of the body, the propeller shafts passing lengthwise parallel with the body and being provided each with a chain wheel 67 and front and rear propeller blades 67' and 67².

68 is a centrally located propeller shaft suitably mounted in the body and passing longitudinally within the engine room. This shaft carries a propeller blade 68' located at the forward end and immediately behind the elevating rudder and is fitted also with chain wheels 69 and 69' for a purpose later explained. The engine shafts in both instances project at either end through the crank casings and are fitted with specially designed clutch members now described and best shown in Figs. 12 and 13 of the drawings.

70 is a male clutch member rotatably mounted on the protruding end of the engine shaft and prevented from end displacement by means of a collar 70' shrunk on the shaft.

71 is a band or ring slipped onto one end of the said clutch member which is contracted to receive it and 71' is a cylindrical shell screw threaded onto the end of the clutch member and holding the band in position. The shell has the extending end coned out to present a coned face 71^x designed to engage with the beveled face 72^x of a female clutch member 72 feathered on the end of the shaft and rotatable therewith. The band and the female clutch member are connected by fly balls 73' carried by links 73 attached to the respective parts. The shell is supplied with extending spring catches 74 designed when the clutch members are engaged to spring into suitable

notches 74' presented by the female clutch member. The male clutch member is supplied with chain wheels 75 and 75' while the female clutch member is formed with a flange or disk 72°.

76 is a pivoted lever having the lower end thereof forked and bearing on the face of the disk and the upper end thereof receiving a screw 76' attached by means of a spring 76² to the body of the engine and 75 fitted with an adjusting nut 76^x. The spring and lever are designed to act against the fly balls. The tension of the spring can be adjusted at any time by adjusting the nut 76^x. The faces 71^x and 72^x when engaged cause 80 the male clutch member to rotate with the female clutch member. In order to insure a positive drive when these parts are engaged I have supplied the adjacent ends of the clutch members with engaging teeth 77. 85 The chain wheels 75 and 75' of the clutches to the rear of the engines are connected by chains 78 and 78' with the chain wheels 67 of the outstanding propeller shafts. The clutch members in advance of the engines 90 are connected through chains 79 and 79' with the chain wheels 69 and 69' hereinbefore referred to. In this way the forward clutches in each case control the front propeller while the rear clutches control the side or outstanding propellers. Controlling levers as now described are located adjoining the front clutches in each instance.

80 and 81 are levers mounted on a cross shaft 82 carried in suitable bearings 82' located on the floor of the engine room. The lever 81 is secured to the shaft so that when operated the shaft is caused to rotate with the lever. The lever 80 is rotatably mounted on the shaft and carries a spring pressed 100 locking pin 83 designed to enter a socket 83' formed in the lever 81, the pin when so engaged effecting the locking of the one lever to the other.

In order that the pin can be held in a 110 withdrawn position I have fitted it with an arm 83^x normally countersunk in the face of the lever 80 but designed when the pin is withdrawn and turned to engage with the face of the lever and retain the end of the 115 pin free of the socket.

84 is a quadrant presenting a pair of guide slots 84' and 84² which receive the levers. The lever 81 is supplied with a specially constructed spring pressed detent 85 engageable with and operating over teeth 86 presented by the quadrant. The lever 80 carries an adjusting screw 86' which extends through a slot 86² formed in one of the quadrant guides. By tightening the screw 120 at any location one can fix the position of the lever 80. The detent 85 is designed so that when withdrawn from the teeth and turned one half turn and released it will be completely clear of the teeth. The shafts 130

82 carry outstanding forked arms 82^x arranged to bear against the face of the flanges or disks 72' of the front clutch members. The levers 80 are connected by an adjustable link 87 so that the front levers can be manipulated by the movement of the back levers.

The levers 81 are connected through links 81° with levers 88 adjoining the back clutches in each instance, the latter levers extending from cross shafts 88' mounted on the engine room floor and fitted with forked arms identical to those 82^x and bearing on the flanges of the rear clutches.

15 It will be seen from the above connections that if the locking pins 83 are in the sockets the clutch members of both engines can be controlled by manipulating either one or other of the levers and also that if the locking pins are withdrawn and locked out of the sockets it is necessary to independently manipulate each of the levers 80 and 81 to control the clutches.

I wish now to explain the action of the 25 parts best shown in Fig. 12 of the drawings assuming the engines running and the shafts 62' and 63' rotating. It will be seen that the female clutch members are caused to rotate with the shafts the male clutch 30 members remaining stationary, while the band slips in respect to them. However as soon as the engine shafts have gained sufficient speed to cause the fly balls to counteract the actions of the springs 76° the female 35 clutch members will fly in and engage with the male clutch members and consequently rotate them effecting the rotation of the propellers. This insures that the driving load will not be placed on the engine until 40 it has picked up or reached a certain speed of rotation, the time at which the engagement of the clutch members occurs depending entirely on the adjustment of the springs.

In the above explanation it is considered 45 that the levers are placed in a position to allow the female clutch members to slide on the shaft to engage with the male clutch members, this action not being possible unless the outstanding forked arms controlled 50 by the levers 80, 81 and 88 are withdrawn away from the disks or flanges. On the other hand by retaining the last mentioned forked arms in a position engaging with the disks and with the levers locked the 55 engines can be running without driving the propellers as will readily be understood.

I have considered it advisable to control the supply of gasoline fed to the engines in a manner such that both engines will get 60 the same firing mixture.

In Figs. 14 and 15 carburetors 89 and 90 are shown, these being connected to the intake manifolds of the engines in the ordinary way and to the gasoline feed pipe 91 65 which leads to the gasoline tank 10 already

referred to. I do not wish to enter into the detailed construction of these carburetors other than that I wish to state the valves controlling the feeding of the gasoline are regulated and controlled by an adjusting rod 92 fitted with worms 93 or other such contrivances arranged to open or close the valves of the carburetors an equal amount in both engines upon the adjusting rod being turned by means of the hand wheel 94 located at the rear end thereof. A graduated scale 95 is also supplied on the carburetors and the valves thereof are fitted with index pointers 95' which operate over the scales. In this way reading can be taken at any time to show exactly what quantity of gasoline is being fed to the engines. I have supplied the engines also with speed counters 96, these being of any approved form. In the above way I am able to synchronize 85 so to speak the two engines as the engineer in charge can readily detect by taking readings both from the carburetors and from the speed indicators any change which might occur in the operation of the engines. 90

I consider it very important in devices of this kind to have all the engines operating under the same conditions and as nearly alike as possible. Although I have only described two engines it will be understood 95 that any number of them might be connected up in the same manner as the two herein shown and further any number of side propellers could be used in conjunction with the engines, the number depending on the 100 propulsion required.

I wish it to be noted that the forward and rear ends of the body are rounded and that the forward and rear ends of the wings 2 and 3 are brought to an edge. This effects 105 the easy passage of the airship through the air in flight as will readily be understood by those familiar with the operation of dirigibles.

When the airship is in actual flight the 110 forward rudder is manipulated for ascending or descending while the rear rudder is used for turning purposes. The forward rudder is shaped to cut through the air with a minimum resistance while the rear rudder 115 is constructed to present a large air resistance and effect a quick and positive turning of the airship.

It will be noticed that the engines and 120 cabins all appear below the wings. This effects stability in flight as any turning movement around the longitudinal axis of the dirigible is immediately counter-acted by the extending wings.

What I claim as my invention is:—

1. In a dirigible airship a cylindrical gas containing body sub-divided by cross partitions into distinct sections and having the sections individually sub-divided by a plurality of partitions into a plurality of com- 125 130

partments, means for separately inflating the sections and valve controlled means connecting the adjacent compartments of the respective sections, as and for the purpose specified.

- 5 2. In a dirigible airship, a cylindrical gas containing body sub-divided by cross partitions into distinct sections and having the sections individually sub-divided by a plurality of partitions into a plurality of compartments, a feed pipe, a branch pipe for each section leading from the feed pipe, valve controlled inlet pipes connecting the branch pipes with the compartments and valve controlled means connecting the compartments of adjacent sections, as and for the purpose specified.

- 10 3. In a dirigible airship, in combination a cylindrical gas container having adjacent longitudinally disposed outstanding side wings opening to the interior of the container and partitions passing across the container and wings and dividing the same into a plurality of gas sections, as and for the purpose specified.

- 20 4. In a dirigible airship, in combination, a cylindrical gas container having longitudinally disposed outstanding side wings opening to the interior of the container, partitions passing across the container and wings and dividing the same into a plu-

rality of gas sections, and further partitions in the respective sections sub-dividing the sections each into a plurality of compartments, as and for the purpose specified.

5. In a dirigible airship the combination with a gas container or body, of an expansion chamber mounted on the body, gas pipes connecting the expansion chamber with the body, spring pressed ball valves located in the pipes and spring pressed pop valves inserted in the pipes and designed to release under excessive pressure the gases in the expansion chamber to atmosphere, as and for the purpose specified.

6. In a dirigible airship the combination with a gas container, of an expansion chamber mounted on the container, an automatically controlled connection between the container and the expansion chamber designed to release the gas under excessive pressure in the container to the expansion chamber and automatically operated means designed to release the gas under excessive pressure in the expansion chamber to atmosphere, as and for the purpose specified.

Signed at Winnipeg, this 31st day of January, 1914.

JOSEPH SPITERI.

In the presence of—
J. CONTI,
G. S. BOXBURGH.
